TIRE

Yoshio Oita, Kobe, Japan, assignor to The Dunlop Company Limited, Fort Dunlop, Erdington, England, a British corporation

Filed Feb. 10, 1969, Ser. No. 15,705

Claims priority, application Japan Aug. 26, 1968

Term of patent 14 years

Int. Cl. D12—14

U.S. Cl. D90—20

FIG. 1

FIG. 2

FIG. 3

FIG. 4

FIG. 5

FIG. 6

FIGURE 1 is a fragmentary plan view of a tire showing my new design;

FIGURE 2 is a fragmentary bottom plan view thereof;

FIGURE 3 is a fragmentary side view thereof;

FIGURE 4 is a fragmentary view of the opposite side thereof;

FIGURE 5 is an end view thereof as seen from the left of FIGURE 3; and

FIGURE 6 is an end view thereof as seen from the right of FIGURE 3.

It is to be understood that the design shown in all views continues around the tire circumference.

I claim:

The ornamental design for a tire, as shown and described.
